UNITED STATES PATENT OFFICE.

EDWARD CARY, OF NEW YORK, N. Y., ASSIGNOR TO ALICE GILBERT AND CHARITY CARY, OF SAME PLACE.

THERMOSTAT.

SPECIFICATION forming part of Letters Patent No. 614,288, dated November 15, 1898.

Application filed September 16, 1897. Serial No. 651,915. (No model.)

To all whom it may concern:

Be it known that I, EDWARD CARY, a citizen of the United States, and a resident of New York city, county of New York, and State of New York, have invented certain new and useful Improvements in Thermostats, of which the following is a specification, reference being had to the accompanying drawings, forming a part thereof, in which similar letters of reference indicate corresponding parts.

This invention relates to that class of thermostats or analogous apparatus which are designed to automatically indicate the overheating of bearings in engines and other mechanisms by sounding an alarm; and it has special relation to an improved thermo-electric device designed for direct application and use upon the connecting-rod of an engine to indicate overheating of the crank-pin bearing.

The object of my invention is to provide a simple and improved mechanism of the above character which will in its general construction and arrangement be adapted for direct combination with and application to the connecting-rod of an engine and which will operate to automatically complete an electric circuit and sound an alarm during the operation of the connecting-rod whenever the crank-pin bearing becomes overheated.

In the drawings, Figure 1 is a side view showing the connecting-rod, crank-pin, and adjacent parts of an engine with my improved mechanism in position. Fig. 2 is a detail side view of the crank-pin end of a connecting-rod having my improvements. Fig. 3 is a detail transverse sectional view taken on the line 3 3, Fig. 2. Fig. 4 is a detail top or plan view of the thermo-electric device. Fig. 5 is a detail longitudinal sectional view taken on the line 5 5, Fig. 4.

Referring to the drawings, A designates the connecting-rod of an engine, B the crank, and C the crank-pin, these parts being arranged and connected in any suitable or usual manner and the rear end of the connecting-rod being connected to a sliding cross-head D, moving in a cross-head frame E, in the usual manner.

50 My improved thermo-electric device F comprises a strip or plate of vulcanized or hard

rubber or any other suitable non-conducting substance, as shown at f, which strip or plate is surmounted by corresponding metallic strip or plate f'. The plates f and f' may be secured together in any suitable manner, preferably by means of pins, as shown at f², passing downwardly from the metallic top plate f' into the non-conducting bottom plate f.

The device F is secured directly upon the connecting-rod, preferably at the top, directly above or adjacent to the crank-pin upon bearing, in any suitable manner, preferably by means of a screw G, passing through an opening f³ in the insulating-plate f at the rear end 65 of the device and into the connecting-rod, as shown in Fig. 2, this securing-screw being insulated from the metallic top plate f' by cutting away the latter at the part surrounding the head of the screw, as shown at f⁴.

The thermo-electric device F, when secured in position upon the connecting-rod, is thus completely insulated from the latter.

Upon the connecting-rod A, adjacent to the device F and preferably at the front end of the latter, I secure in any suitable manner a contact-plate H, which is preferably formed by a right-angular plate having its top arm 75 projecting over the front end of the device F, as shown in Figs. 1 and 2.

A line-wire I, comprised in an electric circuit, is connected with the metallic plate f', preferably at the rear end of the latter, and is carried rearwardly along the connecting-rod A to a point near the cross-head D, this 85 line being insulated from and connected to the connecting-rod in any suitable or desired manner. The rear end of the line-wire I has a flexible connection, as at i, with an arm J, carried by and insulated in any suitable manner from the cross-head D and projecting therefrom, so that it will continuously slide upon or contact with, during the movement 90 of the cross-head and connecting-rod, a metallic plate K, carried upon and insulated from the cross-head frame E. The plate K is preferably arranged in longitudinal position at the side of the lower portion of the stationary cross-head frame E, and from one of its ends extends a line-wire L, comprised 95 in a battery-and-bell electric circuit, the other end of said line-wire L being connected to

100

any suitable stationary part of the engine—for instance, as shown at L, Fig. 1.

The alarm-bell or annunciator M comprised in the electric circuit may be arranged at 5 any suitable or desired point.

The operation and advantages of my invention will be readily understood by those skilled in the art to which it appertains. When the crank-shaft bearing becomes over-heated the plate device F will expand and consequently rise at its free end, so that the metallic plate f' comprised in the electric circuit will contact with the contact-plate H, thus completing the circuit through the wires 10 I L and devices J K and through the frame or parts of the machine and sounding the alarm.

It will be noted that by reason of the improved construction and arrangement of parts as comprised in my invention and its special 15 adaptation to the moving connecting-rod the mechanism will operate effectively and automatically as an alarm connection between the moving connecting-rod and stationary parts of the engine to indicate any overheating of 20 the crank-shaft bearing at the outer end of the connecting-rod.

Having thus described my invention, what I claim as new, and desire to secure by Letters 25 Patent, is—

30 In an improved thermo-electric device of the class described, the combination with the

connecting-rod, cross-head and frame of an engine, of a non-vibrating thermostat secured to the connecting-rod at a point adjacent to the crank-pin bearing and insulated from 35 said rod, an insulated line-wire connected with said thermostat and carried upon and insulated from the connecting-rod, an arm projecting from the cross-head and insulated therefrom and having a flexible connection 40 with the wire upon the connecting-rod, the contact-plate carried by the frame of the engine and insulated therefrom against which said arm bears during the sliding movement of the cross-head, a line-wire comprised in 45 the electric circuit and extending from said contact-plate and connected with the frame or parts of the engine, and a contact-plate mounted upon the connecting-rod with relation to the thermostat and operating to complete the circuit through the frame or parts of the engine, substantially as and for the purpose set forth.

In testimony that I claim the foregoing as my invention I have signed my name, in presence of two witnesses, this 13th day of September, 1897.

EDWARD CARY.
